UNITED STATES PATENT OFFICE

2,457,486

GARMENT HANGER

Kathleen R. O'Grady, Chicago, Ill.

Application July 19, 1946, Serial No. 684,702

3 Claims. (Cl. 223—92)

1

This invention relates generally to garment hangers and it is more specifically directed to garment hangers particularly adapted to support women's garments having padded shoulders and large neck openings.

Many women's dresses and coats are of the type having padded shoulders and rather large neck openings. Conventional types of coat hangers are notoriously ill adapted for supporting such garments. Unless considerable care is taken in placing such garments upon the conventional coat hanger, and the hangers with such garments thereon are handled with considerable care, the garment will readily slip off to one side or the other of the hanger and fall to the floor.

When a garment has a small neck opening, it is not as likely to slip completely off from the hanger. But even so, the shoulder pads will not be properly supported and the dress will hang unevenly. This is not only detrimental to the garment, but also gives a very untidy appearance.

I am aware that a large variety of garment hangers are available, but have not found a hanger among the many designs which is suitable for supporting women's garments of the types having padded shoulders and large neck openings.

Accordingly, the object of my invention, generally stated, is the provision of an improved garment hanger capable of supporting and retaining thereon in proper position, without likelihood of slipping off, women's garments of the types having padded shoulders and large neck openings.

More specifically, an important object of the invention is the provision of an improved form of garment hanger having end supports with upstanding flanges, and open centers, so as to receive and retain the shoulder pads of garments hung thereon.

Yet another important object of the invention is the provision of an improved form of garment hanger having end supports for garment shoulder pads which securely support such pads with a minimum surface thereof engaged, thereby allowing the air to have full access to a large portion of the areas of such pads.

Other objects of the invention will, in part, be obvious and will in part appear hereinafter.

For a more complete understanding of the nature and scope of my invention, reference may now be had to the following detailed description thereof taken in connection with the accompanying drawings, wherein:

Figure 1 is a side elevational view of a gar-

2

ment hanger forming one embodiment of the invention, showing in broken outline a garment having shoulder pads, having therefrom;

Figure 2 is a top plan view of the garment hanger shown in Figure 1;

Figure 3 is an end elevational view of the hanger shown in Figure 1; and

Figure 4 is a sectional view taken on line 4—4 of Figure 2.

In the drawings, a garment hanger forming the preferred embodiment of my invention, is indicated generally at 5. I prefer to form the hanger 5 as an integral, one-piece body from a suitable plastic material. The hanger may be molded from such plastics as: the acrylate resins; vinyl acetates; vinylidene chloride polymers and copolymers; polystyrene polymers; and polyethylene polymers. Other types of plastics materials may be used, and other material such as wood, metal and strong cardboard may also be used. However, from the standpoint of attractiveness, non-breakability, availability, and expense in manufacture, I prefer to use one of the plastics indicated above.

The essential structural parts of the hanger 5 are the transverse support member or section 6 and the two shoulder pad supports 7, extending in a horizontal plane from the opposite ends thereof. It is also desirable to provide suitable means for suspending the hanger 5, such as the conventional integrally formed hook 8.

The transverse support member 6 is preferably provided with an outwardly bowed or bulged portion 10 so as to provide a supporting surface 35 on one side of the hanger 5 which simulates the shape of the base or lower portion of a human neck between the shoulders. The bulge 10 thus provides, in combination with the shoulder pad supports 7, a complete support for garments of the class described.

The shoulder pad supports 7 carried on the opposite ends of the transverse support member or section 6, constitute the most important feature of the invention. In plan view, the outline of the supports 7 may be said to correspond to the shape of an acorn with the apex or pointed end attached to the support member 6. Although this is the preferred shape for the pad support 7, the advantages of the invention can also be obtained by having these parts in the form of other shapes, such as circular or elliptical. Desirably, the shoulder pad supports 7 may have a length of 4" and a width of 3".

The most significant features of the shoulder pad supports 7 are the flanges 11, which upstand

around the peripheries thereof, and the large open areas 12 formed in the centers of the pads. At the outer ends of the supports 7, the height of the flange 7 is increased materially at 13 so as to provide greater endwise support for the shoulder pads of a garment hanging on the hanger 5. That is, the flanges 13 prevent the shoulder pads from slipping over the ends of the hanger 5.

The shoulder pad supports 7 should extend or lie in a horizontal, or near horizontal plane, in contradistinction to being sloped downwardly, as in the conventional construction of coat hangers. The bottom of each of the shoulder pad supports 7 is preferably in the form of the inwardly turned flange 14 of such width as to leave the relatively large opening 12.

When a garment is supported upon the hanger 5, as indicated in broken outline in Figure 1, the shoulder pads 15 of the garment seat within the flange 11 and sag into the openings 12. The upstanding ends 13 catch under the outer ends of the shoulder pad 15. The neck of the garment fits around the bulged portion 10 as indicated at 16 in Figure 1, while the main portion of the garment hangs down from the hanger 5 as indicated at 17.

It will be seen that the combination of the upstanding flange 11 and the central opening 12 of each end 7 serve to securely receive the shoulder pads 15. However, the retaining surfaces engaged are relatively small so that the pads are exposed for the greater part of their surface areas. This permits any retained perspiration to be quickly vaporized.

With a hanger of conventional design, the garment would tend to slip off to one side or the other of the hanger. However, in the construction shown, the shoulder pads of the garment are supported and retained in the supporting ends, thereby retaining the entire garment in place. When desired, the garment may be readily removed from the hanger 5.

Although I have shown and described only one specific embodiment of the invention, it will be understood that it may be provided in other forms so long as shoulder pad end supports are provided having a relatively high upstanding flange and a relatively large central opening.

I claim:

1. A garment hanger particularly adapted to support women's garments having padded shoulders, comprising in combination, a transverse support member, and enlarged shoulder pad supports extending from the opposite ends of said transverse support member, said shoulder pad supports lying generally in a horizontal plane and each having a relatively large central opening surrounded by an inwardly turned flange having an upwardly turned flange upstanding therearound for the greater part of the periphery thereof, so as to retain garment shoulder pads therein.
- 15 2. The construction of claim 1 wherein said upwardly turned flange on each of said shoulder pad supports is of substantially greater height at the outer end thereof than at the sides thereof.
- 20 3. A garment hanger particularly adapted to support women's garments having padded shoulders and large neck openings, comprising in combination, a transverse support member having an outwardly bulged portion so as to provide a supporting surface simulating the base of a human neck, and shoulder pad supports extending from the opposite ends of said transverse support member, said shoulder pad supports lying in a generally horizontal plane and each having a relatively large central opening surrounded by an inwardly turned flange having a relatively high upwardly turned flange upstanding therearound for the greater part of the periphery thereof so as to retain garment shoulder pads therein.
